UNITED STATES PATENT OFFICE.

CHARLES R. BAKER, OF ABILENE, KANSAS.

COOP.

1,040,489.

Specification of Letters Patent.

Patented Oct. 8, 1912.

Application filed July 15, 1911. Serial No. 638,696.

To all whom it may concern:

Be it known that I, CHARLES R. BAKER, a citizen of the United States, residing at Abilene, in the county of Dickinson and State of Kansas, have invented certain new and useful Improvements in Coops; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to chicken coops and more particularly to an outdoor coop for housing a hen and brood of chicks; the principal objects of my invention being to provide a device of that character, wherein the 20 hen may be confined while allowing the chicks to run free; in which the entire front of the coop is easily and quickly removed, the upper part of the front being hinged in order that a person may work with the 25 chickens without removing the entire front of the coop; in which the floor is removable, and which is provided with an adjustable hood for protecting the interior of the coop from sun or rain.

30 It is a further object of my invention to provide other improved details of structure hereinafter described and illustrated in the accompanying drawings, wherein:

Figure I is a perspective view of a coop 35 constructed according to my invention, showing the hood lowered over the front of the coop in full lines, and in extended position in dotted lines, the chick door being closed. Fig. II is a similar view with the 40 hood removed, the chick door open, and the upper portion of the front shown in its open position in dotted lines. Fig. III is a section on the line III—III, Fig. II, the floor being shown partially removed in dotted 45 lines. Fig. IV is an enlarged detail view of the front lower part of the coop, with the front door spaced slightly therefrom. Fig. V is a detail view of the sliding chick door.

50 Referring more in detail to the parts:—1 designates the body of the coop, which is preferably formed of sheet metal and has a top sloping downwardly toward the rear; the top, sides and rear end being preferably 55 so connected that they may be easily and quickly separated, in order that the coop

may be knocked down for shipping or storing. The sides 2 extend downwardly below the back member 3 and have upturned flanges 4 spaced from the bodies of the sides 60 to form the parallel grooves 5, each side having a stamped out lip 6 at its front end, which is turned inwardly above the flanges 4 and spaced slightly therefrom.

7 designates the bottom of the coop, which is preferably of flat sheet metal and has edge flanges 8 turned downwardly and adapted to slide in the grooves 5, in the sides 2. At the front edge of the bottom 7 is a down-turned flange 9, against which the front of 70 the coop is adapted to abut, and pivotally mounted on the back member 3 is a latch 10, which is adapted to hang over the rear edge of the bottom when the latter is in place to prevent its accidental removal. 75 Each of the side members 2 is turned inwardly at the front to form the rails 11, which limit the forward movement of the bottom 7 and form a back for the front of the coop; each of the rails being provided 80 with an aperture 12, for a purpose presently set forth.

13 designates the body portion of the front of the coop, which is preferably formed of a metal frame having a mesh center, one edge of the frame having back turned flanges 14, adapted to project over the sides of the coop when the front is in place. Mounted on one side of the frame is a pin 15, which is adapted for projection 90 into the aperture 12, in the side flange 11, when the front is in place, and mounted on each end of the frame is a hook 16 which is adapted for connection with an eye 17 on the inside of the coop, to hold the front in 95 place. The mesh 13', on the front frame 13, extends only partially across the front, one end being left open to provide a door opening. Fixed to the frame, above the end having the door opening, is a hanger 18 100 comprising a piece of sheet metal having its lower portion bent forwardly and turned back at the bottom, the back turned part having a forwardly directed lip for forming a slide lock for the chick door. The 105 chick door 19 is preferably composed of a piece of sheet metal having a central opening, covered with wire mesh, and having the hooked upper end 20 adapted for sliding cooperation with the hanger 18. Fixed to the 110 lower rail of the frame 13 is a guide strap 21 which holds the sliding door 19 to the

frame, while permitting free sliding movement thereof. Hinged to the upper part of the frame 13 is a door 22; also of mesh construction, the upper part of the door being 5 adapted for abutment against a member 23 which depends from the roof of the coop, over the upper part thereof. Pivotaly mounted on the member 23 is a hook 24 which is adapted for attachment to an eye 10 25 on the upper part of the frame 22, to hold said frame in place and entirely close the front of the coop.

At the front, the top of the coop is provided with a roll 26 having an upturned flange 27 at its lower edge and spaced from 15 the body to provide a channel 28.

29 designates a hood having a hooked upper part 30 adapted to slide into the roll 26 from the end, and having a lip 31 for 20 holding against the roll flange 27. Mounted on the edge of hood 29 is a hook 32, which is adapted to take into a back eyelet 33, on the side of the coop, to hold the hood tightly over the front, or into a front eyelet 34, to hold the hood slightly open, as 25 illustrated in dotted lines in Fig. I.

In using a coop of this construction, presuming the parts to be assembled as described, a hen is placed within the coop 30 with a brood of chicks, and the small door 19 moved back to allow the chicks free ingress and egress from the coop, while confining the hen therein. Should it be desired to work with the chickens without 35 removing the hen from the coop, the upper door 22 may be swung back on its hinges, so that an attendant may have access to the interior without allowing the chickens to escape. Should it be desired to protect 40 the coop from sun or rain, the hood 29 may be slipped into the roll 26, so that it may hang flush over the front of the coop, as 45 illustrated in Fig. I, or may be inclined thereover, as shown in dotted lines in the same figure, according to the degree of protection it is desired to give.

It is apparent that the bottom portion 7 50 may be removed from the coop body and that the entire front may be removed by unfastening the hooks 16 and 24.

Having thus described my invention, what I claim as new therein and desire to secure by Letters-Patent is:—

1. A coop comprising a body portion having a top provided with a roll at its front edge projecting in front of the body portion and having a conveyer flange spaced from its body, a hood having a conveyer

flange slidably mounted on the roll flange, a hook on the end of said hood, eyes on one 60 side of the coop adapted for receiving said hook, a member fixed to the coop body and covering the upper part of the front thereof, and a removable mesh front member adapted for closing the remainder of said 65 opening.

2. A coop comprising a body member having an open front, and a front member for closing the body member, said front member hinged at its center part to form 70 upper and lower portions, said lower portion adapted for attachment to the coop body and provided with a chick door, and a hook and eye on the body member and the upper portion for securing said upper 75 portion in closed position.

3. A coop comprising a body member having a top provided with a roll at its front edge projecting in front of said body member, a mesh front member, hinged at 80 its central part to form upper and lower portions, said lower portion provided with a chick door and attached to the body member, and a hood provided with a hooked upper portion adapted to be pivotally mounted 85 within said roll of the body member.

4. A coop comprising a body portion, having a top provided with a roll at its front edge, the said roll formed integral with said top and projecting in front of the 90 body portion, and having a conveyer flange spaced from its body, a hood having a conveyer flange, slidably mounted on the roll flange, and a removable mesh front, hinged at its central part to form an upper and 95 lower portion, the said hood being adapted to swing over said upper portion and the lower portion secured to said body portion and provided with a chick door.

5. A coop comprising a body portion having an open front, a removable mesh member hinged at its central part to form upper 100 and lower portions, said lower portion being provided with an opening and secured to the base of said body portion, a slide door 105 adapted for covering said opening, a hanger roll disposed at the front of said body above said opening, a slide door pivotally mounted in said roll adapted for covering the said upper hinged portion.

In testimony whereof I affix my signature in presence of two witnesses.

CHARLES R. BAKER.
